UNITED STATES PATENT OFFICE.

JOHN A. RHODES, OF ATLANTA, GEORGIA, ASSIGNOR OF ONE-HALF TO JOSEPH S. REYNOLDS, OF ATLANTA, GEORGIA.

POWDER SPRAYER.

Application filed June 23, 1924. Serial No. 721,801.

To all whom it may concern:

Be it known that I, JOHN A. RHODES, a citizen of the United States, residing at Atlanta, in the county of Fulton and State 5 of Georgia, have invented certain new and useful Improvements in Powder Sprayers; and I do hereby declare the following to be a full, clear, and exact description of the invention, such as will enable others skilled 10 in the art to which it appertains to make and use the same.

This invention relates to an apparatus for spraying plants with powder or the like, and has for its object to provide a simple 15 mechanism of this character which will be more efficient in use and less costly to manufacture than those heretofore proposed.

With these and other objects in view, the invention consists in the novel details of 20 construction and combinations of parts more fully hereinafter disclosed and particularly pointed out in the claims.

Referring to the accompanying drawings, forming a part of this specification, in 25 which like numerals designate like parts in all the views:—

Figure 1 is a perspective side view of the device made in accordance with this invention;

Figure 2 is a fragmentary view of the device partly in section showing details of 30 construction;

Figure 3 is a view taken on the line 3—3 of Fig. 1, looking in the direction of the 35 arrows; and

Figure 4 is a diagrammatic view illustrating the use of the device.

1 represents a bellows comprising the collapsible material 2 attached to the back 40 board 3, and the front board 4, all in accordance with the usual bellows construction. The back board 3 carries at its bottom the casting 5 comprising a rectangular-shaped cup portion 6, the bottom of which 45 is extended to form the base 7. The bellows 1 is suitably connected to the cup 6 to form an air-tight joint therewith. The base 7 of the casting 5 is provided on its under side with a circular flange 8 of a 50 size to receive the metallic screw cap 9 of the usual and well known fruit jar 10. The cap 9 is secured in any suitable way to the base 7, as by the rivets 11. The base 7 and the top of the cap 9 are provided with the

registering apertures forming a passage-way 15 located in the bottom of the cup 6. Also they are apertured in a similar manner to provide a passage 16 outside the cup 6 and which may be fitted with the collared bushing 17, the protruding end of which is adapted to receive one end of a flexible tube delivery 20.

To the back board 3 of the bellows 1 is securely fastened the vertically disposed bar 25, to the upper end of which is pinned one 65 end of the curved handle 26 provided with any suitable gripping means 27. The other end 28 of the handle 26 is bent around so as to form the handle 26 in the shape of a letter J as seen in Fig. 1. At the extremity 70 of the end 28, the handle 26 is pinned to the end of a substantially horizontally disposed connecting bar 30, the other end 31 of which is pinned to a bar 32 rigidly secured to the front board 4 of the bellows 1 75 and extending in the same plane therewith. The free end of the bar 32 is bent angularly to form the extension 33 which is apertured at its end to receive the hooked end 1 34 of a spring 35. The other end of this 80 spring 35 is hooked into the extremity 36 of the base 7 of the casting 5. The parts are so constructed that the spring 35 with its supporting bar 32, connecting link 30, handle 26, and bar 25, are substantially in 85 the same vertically disposed plane, as will be clear from Figs. 1 and 3. The bar 32 is suitably apertured above the bellows 1 to receive a link 40 provided at its other end with a hook 41 adapted to engage the eye 90 42 formed in the end of the horizontally disposed extension 43 of the vertically disposed stirring rod or agitator.

An apertured guide plate 47 is positioned at the top central portion of the back plate 3, which serves to support the upper portion of the stirring rod 45, see Figs. 1 and 3. This stirring rod passes through the compressible material 2 of the bellows and extends downwardly within said bellows and through the passage 15 in the bottom of the cup 6, into the jar 10, which is adapted to contain the powder-like material 50 to be applied to the plants. Within the jar 10, the stirring rod 45 is bent to form a U- 100 loop 51 constituting an agitator in order to facilitate the stirring of the material 50. Thus it will be seen that the agitator 51 is 105

adapted to oscillate, through the powder 50, using as a pivot the stirring rod 45 which extends through the bellows 2 as a pivot. The link 40 and the turned-over end portion 43 of the stirring rod 45 are so formed and dimensioned as to be in all instances angularly disposed one to the other.

The flexible hose 20 is bent around and downwardly as clearly shown in Figs. 1 and 2, being held in this position by a hook 55 carried by the end 36 of the base 7, of the casting 5. The end 56 of the hose 20 may be provided with any suitable spraying nozzle such as 57, to suit the needs of the device.

From the foregoing, it will now be seen that the operation of the device is as follows:—Powdered material 50 having been placed in the container 10 and the latter having been screwed into operative position on its cap 9 rigidly attached to the base 7, the operator will take the device to the plants to be sprayed. As clearly shown in Fig. 1, the handle 26 is grasped by the hand, as shown, and the operator then walks down the row of plants to be sprayed. The device will assume a position slightly angular to the perpendicular, and as best illustrated in Fig. 4 in full lines. When a plant is reached upon which the powder is wished to be sprayed, the operator, by a wrist movement, gives a slight kick or throw forward to the device. This action will, due to the weight of the mechanism, cause the container 10 and its attached parts to swing forward, revolving about the pin 60 as a center, but the handle 26 being still retained by the operator, the bar 30 carried thereby and pivoted thereto, will swing upwardly about pin 61 as a center, and as clearly shown by the dotted lines in Fig. 4. The result of this action, of course, will be to compress the bellows 1, forcing the air contained therein through the passage 15 in the bottom of the cup 6, into the jar or container 10. This passage 15 being relatively smaller than the passage 16, the air will be directed in a blast against the powdered material 50, and, in escaping through the tube 20, will carry along with it some of the powdered material.

The kick or throw imparted by the operator is very quick or instantaneous in action, with the result that the weight of the device will return the same to its normal or full line position, as shown in Fig. 4. When the next plant to be treated is reached, the operator repeats his wrist action, thereby giving the device another throw forward, whereupon the bellows will operate as described above and the powdered material 50 will be delivered from the nozzle 57 under the plant. The action imparted to the device by the operator through the wrist movement is very easy, with the result that as the operator walks down a row of young plants

to be treated, the action of the mechanism can be timed in cadence with his walking gait.

In case the powdered material 50 becomes caked or partially solidified in the container 10, the agitator 51 will break up the material 50 so that there will always be dust-like particles of the material picked up by the air from the bellows 1. The action of the agitator is best illustrated in Fig. 3, where the bellows is shown in partial collapsed position. Upon full expansion of the bellows 1, the link 40 will be moved away from the back board 3, and in so doing, will turn the agitator 51 located in the powdered material 50 to such a position as indicated at 65. On the other hand, when the bellows is compressed, the link 40 will force the extension 43 of the stirring rod in a direction indicated by the arrow to such a position as indicated at 66, whereupon the agitator 51 will move to such a position as indicated in dotted lines at 67. Thus, it will be seen that the material 50 is agitated within the container 10 upon each operation of the mechanism automatically.

The spring 35, it will be noticed, in Fig. 4, is placed under tension each time the bellows is compressed. Therefore, the spring 35 operates to aid the opening or return of the bellows to its full or normal position.

The advantages of the device will be obvious but may be briefly summarized as follows. Powder sprayers have generally been so designed that upon applying the powder therefrom said powder will be diffused not only upon a portion of the plant but upon the field as well, and the percentage of powder left on the field as in many instances has been far in excess of that placed upon the plant. This device is small, light in weight, simple in construction, and cheaply manufactured. It is portable and because of its size may be easily carried between the rows of plants to be sprayed.

The control of the powder whereby the same is directed from the nozzle immediately upon the plant is a valuable feature. The nozzle which may be of any height may be so positioned as to apply the powder on the upper as well as on the under side of the leaves of the plant.

A still further advantage is in the container 10 which in this instance has been shown as a well-known type of glass fruit jar. Most every farmer's wife has on hand a quantity of such jars and in case of breakage the replacement of the broken part may be easily made. By using such a jar the contents of the same are always visible and no parts have to be disengaged one from the other to ascertain whether said container needs replenishing.

It is obvious that those skilled in the art may vary the details of construction as well

as arrangement of parts without departing from the spirit of the invention and therefore it is not desired to be limited to the construction shown except as may be required by the claims,

What is claimed is:

1. In a device adapted to spray powder on plants and the like, the combination of a container for said powder; a delivery tube associated with said container; a pump comprising a bellows to force said powder through said delivery tube and onto said plants; a stirring rod extending through said bellows and provided with an agitator for said powder said rod pivotally connected to said pump; and means to actuate said pump and agitator.
2. In a device adapted to spray powder on plants and the like, the combination of a readily detachable container for said powder; a delivery tube associated with said container; a bellows like pump to force said powder through said delivery tube and onto said plants; an agitator for said powder passing through said pump and pivotally connected thereto; and means to actuate said pump and agitator.
3. In a device adapted to spray powder on plants and the like, the combination of a container for said powder; a delivery tube associated with said container; a pump to force said powder through said delivery tube and onto said plants; an agitator for said powder pivotally connected to said pump; and means to actuate said pump comprising a hand grip and a bar rigidly secured to said pump and pivotally joined to said grip.
4. In a device adapted to spray powder on plants and the like, the combination of a container for said powder; a delivery tube associated with said container; a pump to force said powder through said delivery tube and onto said plants; an agitator for said powder pivotally connected to said pump; and means to actuate said pump com-

prising a hand grip, a bar rigidly secured to one side of said pump and pivotally connected to said grip, and a link pivotally connecting said grip to the other side of said pump.

5. In a device adapted to spray powder on plants and the like, the combination of a container for said powder; a bellows like pump associated with said container; a vertically disposed bar projecting upwardly from one side of said bellows; a hand grip pivotally attached to the upper end of said bar, and serving to support the entire device; an inclined upwardly extending bar projecting from the opposite side of said bellows; a link pivotally connected to last named bar and said hand grip; an agitator extending into said container and pivotally connected to said last named bar, whereby when said hand grip is suddenly rocked the entire device is also rocked and said bellows and agitator are actuated.

6. In a device adapted to spray powder on plants and the like, the combination of a container for said powder; a bellows like pump associated with said container; a delivery tube also associated with said container; a vertically disposed bar projecting upwardly from one side of said bellows; a hand grip pivotally attached to the upper end of said bar, and serving to support the entire device; an inclined upwardly extending bar projecting from the opposite side of said bellows; a spring to actuate said bellows in one direction; a link pivotally connected to said last named bar and said hand grip; adapted to actuate said bellows in an opposite direction; an agitator extending into said container and pivotally connected to said last named bar, whereby when said hand grip is suddenly rocked the entire device is also rocked and said bellows and agitator are actuated.

In testimony whereof I affix my signature.

JOHN A. RHODES.
